L. N. DIEHM.

FIREARM.

APPLICATION FILED OCT. 6, 1916.

1,271,678.

Patented July 9, 1918.

UNITED STATES PATENT OFFICE.

LUCIUS N. DIEHM, OF WEST HARTFORD, CONNECTICUT.

FIREARM.

1,271,678.

Specification of Letters Patent.

Patented July 9, 1918.

Application filed October 6, 1916. Serial No. 124,072.

To all whom it may concern:

Be it known that I, LUCIUS N. DIEHM, a citizen of the United States, residing at West Hartford, in the county of Hartford and State of Connecticut, have invented a new and Improved Firearm, of which the following is a specification.

My invention relates more especially to the class of firearms that are manually supported and discharged, and an object of my invention, among others, is to provide a firearm that shall be particularly simple in its construction and efficient in its operation.

One form of firearm embodying my invention and in the construction and use of which the objects herein set out, as well as others, may be attained, is illustrated in the accompanying drawings, in which—

Figure 1 is a view in side elevation, partially in central vertical section, through a firearm embodying my invention.

Fig. 2 is a view in end elevation on plane denoted by dotted line 2—2 of Fig. 1.

Fig. 3 is a top plan view with parts broken away to show the construction and operation of the safety device.

Fig. 4 is a bottom view of the breech-bolt.

Fig. 5 is a perspective view of the firing pin looking at the bottom part thereof.

Fig. 6 is a front view of the breech-bolt.

In the accompanying drawings the numeral 5 indicates the handle of my improved firearm, 6 the trigger guard, 7 the trigger, 8 the receiver, and 9 the barrel, all of which parts, with the exceptions hereinafter noted, may be of any ordinary form and may be composed of any desired material.

The barrel is provided with an extension 10 that projects into the barrel opening in the receiver and in which it is held as by means of a pin 11 extending crosswise in the receiver and through a groove 12 cut across the top of the extension 10. In assembling the parts it is very essential that the barrel shall be accurately positioned so that the pin 11 may be easily inserted, and to this end I provide a hole 13 extending into the forward end of the receiver 8 and which hole receives a positioning pin 14 projecting from the upper part 15 of the barrel. In addition to its function as a positioning member, this pin 14 also aids in retaining the barrel in its proper position, and especially against displacement in a rotary direction.

A breech-bolt 16 is located in an opening 17 in the receiver, this opening 17 being cut

through the receiver from side to side and the breech-bolt 16 being insertible in said opening from the side of the receiver. The breech-bolt has cheek pieces 18 that cover 60 the rear part of the opening 17 when the breech-bolt is in its closed position, and thus inclose a chamber in the receiver, and said cheek pieces pass backwardly on opposite sides of the head 19 of the receiver when the 65 breech-bolt is moved backward. These cheek pieces may be suitably roughened to serve as grip members by means of which the breech-bolt may be manually moved backward. The breech-bolt is held in its forward position as by means of a spring 20 surrounding a bar 21 which is held by the pin 11 extending through a crosswise groove in said bar. The breech-bolt has an opening 22 for a firing pin 23.

This firing pin has an opening to receive a firing spring 24 seated in said opening and projecting thereout and being supported by a rod 25. The firing pin has on its lower side at the rear end thereof, guides 80 26 which are the projecting ends of a rib 27 extending across the bottom of said pin at its rear part. These guides extend into grooves 28 that are formed partially by cutting away the bottom edges of the side parts 85 of the cheek pieces 18 as shown in Fig. 4 of the drawings, so that the shoulders 29, created by this cutaway portion, will each form one side of a groove and the bottom wall 30 of the opening 17 will constitute the 90 other side of each of said grooves.

The cut-away portions of the breech-bolt that partially form the grooves 28 is extended forwardly beyond the cheek pieces 18 and into the main part 31 of said bolt 95 to provide a housing 46 for the rib 27, this housing being of a width greater than that of said rib as shown in Fig. 4 of the drawings, so that when the breech-bolt is forced backward by the exploding gases and the wall 32 of the breech-bolt between the cheek pieces strikes the head 19 of the receiver, the rib 27 will be shielded and will not strike said head, and any liability to injury of the rib is thus avoided. The breech-bolt is cut off in tapered form at the part 33 underneath the firing pin, so that the rib projects below the lower edge of the breech-bolt at this point in position for engagement of the sear 34, the rib thus 110 constituting a firing notch.

The sear 34 is pivotally mounted in the

receiver and may be operated in any desired manner by a connection with the trigger 7, in the construction herein shown, the off-set end 35 of a sear operating bar 50 operatively connecting the trigger with a laterally extending sear tail 47 on the sear. As shown in Fig. 1 the said bar and tail are so formed that backward movement of the bar caused by the trigger will pass the bar 10 underneath the tail, raising this end of the sear and lowering its opposite end to disengage it from the firing pin, while forward movement of said bar under the influence of a trigger spring (not shown) will pass 15 said bar over the sear tail that is held down by the sear spring (see Fig. 1) in position to effect this result. A lip 36 on the back end of the sear is positioned to engage a recess 37 located in the edge of a safety 20 member 38. This safety member extends through the receiver from side to side and has a thread at one end engaging a threaded hole 39 in the receiver. A handle 40 at the other end of the safety member, serves as a 25 means for manually rotating it, this handle having a lug 41 adapted to enter safety recesses 42-43 formed in the side of the receiver and within which recesses the lug is held partly by the spring action of the 30 members. When the handle is in its upper position and the lug 41 is engaged in the recess 43 that side of the safety member that is of full contour will underlie the lip 36 so that the sear cannot be moved sufficiently to disengage its point 44 from the 35 notch 45 in the firing pin. The thread on the end of the member 38 is a right-hand thread and if the handle 40 be moved into its upper or safety position the member 38 40 will be drawn inwardly slightly and the hold of the lug 41 in the safety recess 43 in the receiver will be increased so that it will require considerable force to disengage the handle and move it from this safety position.

As my invention, forming the subject matter of this case, is confined to the firing mechanism including the safety devices and the firing pin, I have not described any 50 means for assembling the parts, as these are fully set forth and described in my Patent No. 1,226,478, dated May 15th, 1917. These parts that facilitate the assembling 55 of the members of the firearm are, however, shown in Fig. 1 of the drawings, and reference is hereby made to my patent above mentioned for any information that may be required concerning the means for assembling the members.

60 In accordance with the provisions of the patent statutes, I have described the principle of operation of my invention, together with the apparatus which I now consider to represent the best embodiment thereof; 65 but I desire to have it understood that the

apparatus shown is only illustrative and that the invention can be carried out by other means.

I claim—

1. A firearm including a receiver with a breech-bolt opening therein, a breech-bolt 70 slidably mounted in said opening, said firearm having guide grooves, a firing pin slidably mounted in the breech-bolt, and laterally projecting guides from the firing pin 75 extending into said grooves.

2. A firearm including a receiver with a breech-bolt opening therein comprising a chamber back of the breech-bolt, a breech-bolt 80 slidably mounted in said opening, said chamber having guide grooves in its walls, a firing pin slidably mounted in the breech-bolt, and laterally projecting guides from the firing pin 85 extending into said grooves.

3. A firearm including a receiver with a breech-bolt opening therein, a breech-bolt 90 slidably mounted in said opening and having recesses forming portions of guide grooves, said bolt being positioned so that the bottom wall of the opening in the receiver forms walls of said grooves, a firing pin slidably mounted in the breech-bolt, and laterally projecting guides from the firing 95 pin extending into said grooves.

4. A firearm including a receiver having an opening therein, a breech-bolt slidably mounted in said opening and having cheek pieces with recesses in the cheek pieces forming portions of guide grooves at the 100 bottom edge of said cheek pieces, the bottom wall of the opening in the receiver forming walls of said grooves, a firing pin 105 slidably mounted in the breech-bolt, and guides projecting laterally from the lower part of the firing pin into said grooves.

5. A firearm including a receiver having a breech-bolt opening therein, a breech-bolt 110 slidably mounted in said opening and having cheek pieces on opposite sides of the breech-bolt providing a space between said cheek pieces and with recesses cut into the lower edges of the facing walls of said cheek pieces to partially form guide grooves, one 115 wall of each of which grooves is formed by the edge of said opening in the receiver, and a firing pin movably mounted in the breech-bolt and having laterally extending guides projecting into said guide grooves.

6. A firearm including a frame, a safety 120 member rotatably attached to the frame and having a screw thread for attaching it in place, said safety member having a recess, a sear mounted in the frame and having a projection to enter said recess and to engage 125 the full part of the safety member to prevent movement of the sear, and a retaining member to hold the safety member in its different positions, said thread being arranged to cause increased hold of the re- 130

taining member when the safety member is in position to prevent movement of the sear.

7. A firearm including a receiver having an opening therein, a breech-bolt slidably mounted in said opening and having recesses in its under surface forming portions of guide grooves and a housing opening out of said grooves, said bolt being so positioned that walls of the opening in the receiver forms walls of said grooves, and a firing pin slidably mounted in the breech-bolt, and having a rib extending across the bottom of the firing pin in position to enter said housing, said rib having projecting ends entering said grooves.

8. A firearm including a receiver with a breech-bolt opening therein, a breech-bolt slidably mounted in said opening and having recesses in its lower edge forming portions of guide grooves and a housing opening out of said grooves, said bolt being positioned so that the bottom wall of the opening in the receiver forms walls of said grooves, a firing pin slidably mounted in said breech-bolt and having a rib extending across it of a width to be completely received in said housing, and projecting guides constituting extensions from said rib, said guides extending into said guide grooves.

9. A firearm including a receiver with a breech-bolt opening therein, a breech-bolt slidably mounted in said opening and having cheek pieces with recesses formed in the lower edges thereof facing each other and constituting portions of guide grooves and with a housing opening from said recesses into the main body of the breech-bolt, said bolt also having a hole for a firing pin, and a firing pin located in said hole and having a rib projecting into said housing and below the back edge of the breech-bolt, said rib being of a width less than that of said housing, said breech-bolt being cut-

away underneath said hole so that the rib projects below said cut-away portion in position to be engaged by a sear, and laterally projecting guides constituting extensions from said rib, which guides enter said grooves.

10. A firearm including a receiver having an opening therein comprising a chamber at the rear part of the receiver, a breech-bolt slidably mounted in said opening, said chamber having guide grooves and a housing in its walls, a firing pin slidably mounted in the breech-bolt, and a rib extending across the firing pin and positioned thereon to enter said housing and having projecting ends entering said grooves.

11. A firearm including a receiver with a breech-bolt opening therein comprising a chamber back of said bolt, a breech-bolt slidably mounted in said opening and having cheek pieces, said chamber having grooves in its walls and a housing opening from said grooves into the body of the breech-bolt, said bolt also having an opening for a firing pin, and a firing pin located in said hole and having a rib projecting into said housing, said rib being extended with its ends projecting into said grooves.

12. A firearm including a receiver with a breech-bolt opening therein comprising a chamber back of the breech-bolt, a breech-bolt slidably mounted in said opening and having cheek pieces, said chamber having grooves in its walls, a housing opening from said grooves and located in the body of the breech-bolt, said bolt also having a hole for a firing pin, a firing pin located in said hole and having a rib projecting into said housing and below the back edge of the breech-bolt, said rib being of a width less than that of said housing, and laterally projecting guides constituting extensions from said ribs and entering said grooves.

LUCIUS N. DIEHM.
